ATTORNEY

UNITED STATES PATENT OFFICE.

CLARENCE ROSS BRYANT, OF CHICAGO, ILLINOIS.

WRENCH.

Application filed December 18, 1920. Serial No. 431,665.

To all whom it may concern:

Be it known that I, CLARENCE ROSS BRYANT, a citizen of the United States, residing at Chicago, in the county of Cook and 5 State of Illinois, have invented new and useful Improvements in Wrenches, of which the following is a specification.

This invention relates to wrenches of the spanner type and an object of the invention 10 is to provide a wrench which is particularly adapted for the turning of nuts in close places, the nut turning means of the wrench being arranged to permit a relatively large number of nut engaging positions of the 15 wrench thereby permitting the turning of the wrench in a relatively small place.

More specifically the invention comprehends the provision of a wrench which 20 has nut turning means of uniform size on each end of its handle, the angled faces of the nut turning means on one end of said handle being disposed at an angle to the faces of the nut turning means on the opposite end of the handle equal to substantially 25 one-half of the degree of the angle of the faces of each nut engaging means one to the other.

Another object of this invention is to 30 provide a wrench as specified which is adapted for co-operation with sockets of various sizes for engagement with nuts of various sizes, the said sockets being provided with uniform portion for engagement by the wrench proper, thereby permitting the 35 use of a single wrench with a plurality of sockets of different sizes allowing the wrench to be packed in a relatively small space for carrying about.

Other objects of the invention will appear 40 in the following detailed description and in the accompanying drawings wherein:

Fig. 1 is a plan of the improved wrench.

Fig. 2 is a side elevation of the wrench.

Fig. 3 is a section through a socket 45 employed with the wrench.

Fig. 4 is a bottom plan of the socket.

Fig. 5 is a side elevation of the socket.

Fig. 6 is a section through a socket showing a fragment of the wrench associated 50 therewith.

Fig. 7 is a plan of a modified form of the wrench.

Fig. 8 is a side elevation of the modified form of wrench.

Fig. 9 is a side elevation of a socket

employed with the modified form of the wrench.

Fig. 10 is a plan of modified form of socket.

Fig. 11 is a section through the modified 60 form of the socket.

Fig. 12 is a fragmentary plan of the wrench showing one of its nut turning ends in engagement with the socket.

Fig. 13 is a fragmentary plan of the 65 wrench showing the nut turning end opposite from that shown in Fig. 12 mounted upon the socket and cooperating with the Fig. 12 in illustrating the relative positions of the connecting handle of the wrench when 70 the nut turning means at its opposite ends are in operative engagement with a nut or nut turning socket.

Referring more particularly to the drawing, the improved wrench comprises a connecting handle 1 which has nut turning heads 2 and 3 formed upon its opposite ends and in the preferred form of the invention these nut turning heads 2 and 3 comprise polygonal lateral projections on the handle 80 1. The number of sides of the polyhedral heads 2 and 3 may be varied, depending upon the type of nuts or sockets to be turned, that is they may be rectangular, octagonal, hexagonal or any of the other well known polygonal forms employed in the manufacturing of nuts. In use, the polygonal nut turning heads 2 and 3 cooperate with sockets 4 one of which is illustrated in Figs. 3, 4 and 5 of the drawings. The 85 sockets 4 have their inner surfaces 5 shaped to conform to the shape of the nut turning heads 2 and 3 irrespective of size of the nut engaging portion of the socket 4, the wrench head receiving portions are all uniform, i. e. 90 in the manufacture of the wrenches a plurality of sockets 4 of various sizes may be provided, the sizes of their wrench engaging portions varying in size to fit various sized nuts while all the other wrench head receiving ends are uniform or of the same size to receive the heads 2 or 3 to permit turning of the sockets and nuts engaged thereby, by the wrench structure.

As clearly shown in Fig. 1 of the drawing 105 the angled faces or sides of one of the heads are disposed at an angle to the angular faces of the other head, equal to substantially one-half of the degree of the angle of the faces of each of the heads thus permitting 110

a relatively large number of adjustments of the position of the wrench to permit turning of a nut in a small space; for example, when the heads 2 and 3 are hexagon the relative 5 positioning of the angled faces of one with the other will permit 12 distinct positions of the wrench relative to the nut being turned.

The modified form of wrench illustrated 10 in Figs. 7 to 13 inclusive is also of the spanner type comprising the connecting handle 10 having heads 11 and 12 upon its ends which heads are substantially cylindrical in shape and are provided with polygonal 15 shaped openings 13, the number of sides of each are regulated by the type of nut to be turned.

In use the heads 11 and 12 are adapted to engage over the polygonal portions 14 of 20 nut turning sockets 15 which sockets are provided with polygonal recesses 16 for engagement with nuts to be turned and in practice a number of sockets 15 will be provided which have various sized nut engaging 25 polygonal recesses 16 but in which all of the polygonal wrench engaged portions 14 are of the same size to permit the use of the wrench with a plurality of sockets.

As clearly shown in Figs. 7, 12 and 13 of 30 the drawing, the angled faces of the recesses or openings 13 in the head 11 are disposed, at an angle to the corresponding angled faces of the recesses or openings 13

in the head 12, which angle is equal to, substantially, one-half of the degree of the angle of the faces of the recesses 13 in the head 11 one to the other so that when the head 11 is in engagement with a polygonal portion 14 of the socket 15 the connecting handle 10 will be positioned at an 40 angle to its position when the head 12 is in engagement with the polygonal portion 14 and thus a relatively large number of adjusted positions of the wrench may be had for turning a nut in a small space. 45

It is, of course, to be understood that the invention may be constructed in various other manners and the parts associated in different relations and, therefore, I do not desire to be limited in any manner except as set forth in the claim hereunto appended.

Having thus described my invention what I claim is:

A wrench comprising a handle, a solid polygonal turning head on each end of said handle, the head on one end of the handle projecting in the opposite direction from the handle from the head upon the other end, the angular faces of the head at one end of the handle being disposed at an angle to the angle of the faces of the other head equal to substantially one half of the degree of the angle of the faces on each head one to the other. 50

In testimony whereof I affix my signature.
CLARENCE ROSS BRYANT.
